UNITED STATES PATENT OFFICE.

MAX KRAVITZ, OF PHILADELPHIA, PENNSYLVANIA.

MULTICOLORE-PRINTING PRESS.

1,172,807.

Specification of Letters Patent.

Patented Feb. 22, 1916.

Application filed April 19, 1915. Serial No. 22,494.

To all whom it may concern:

Be it known that I, MAX KRAVITZ, a subject of the Czar of Russia, residing at Philadelphia, in the county of Philadelphia and State of Pennsylvania, have invented new and useful Improvements in Multicolor-Printing Presses, of which the following is a specification.

This invention relates to improvements in multicolor printing presses designed particularly for printing two or more colors in a single operation, the primary object of the invention being to provide a simple, efficient and comparatively inexpensive construction of press of this character which shall be reliable in action and adapted to effect the inking of the form matter and the timed operation of the elements in proper accord to print an absolutely clear impression.

A further object of the invention is to provide a construction wherein the subject matter to be printed is arranged in a plurality of type forms, disposed one in rear of the other, and which are simultaneously inked by sets of inking devices, and in which the action of the press is such that in the printing operation the type matter of the rear form moves through proper guide openings in the front form so that when the parts are in printing position the type matter of the two forms will exactly register for the printing action.

A still further object of the invention is to provide a novel construction and organization of parts, including novel forms of type and spacing devices, and a novel construction and arrangement of form carriers and inking devices, whereby any form matter may be easily and conveniently set up and clean-cut impressions in two or more colors obtained in a single operation, without the objections present in that type of multicolor presses wherein the type matter is arranged in a single form and the sets of inking rollers are thrown into and out of inking position with relation to lines of type on their course of inking motion.

A still further object of the invention is to provide a construction by means of which any portion or portions of a body of matter

to be printed may be printed in a color distinct from the rest, without the necessity of limiting the printing action in distinct colors to different blocks or lines of type, whereby objections incident to prior multicolor printing machines are effectually overcome.

With these and other objects in view, the invention consists of the features of construction, combination and arrangement of parts herein fully described and claimed, reference being had to the accompanying drawings in which:

Figure 1 is a side elevation of a printing press embodying my invention, showing the form fully open or spread. Fig. 2 is a front elevation of the press. Fig. 3 is a vertical longitudinal section of the press. Fig. 4 is a vertical transverse section on the line 4—4 of Fig. 1. Fig. 5 is a top plan view of the press. Fig. 6 is a horizontal transverse section through the forms in open or spread position. Fig. 7 is a similar view of the forms showing the same in closed or printing position. Fig. 8 is a front elevation of the forward form. Fig. 9 is a detail vertical section thereof on an enlarged scale. Fig. 10 shows detail views of the type and spacers employed. Fig. 11 is a side view of one of the inking roller carrier arms. Fig. 12 is a section on the line 12—12 of Fig. 11. Fig. 13 is a horizontal section on the line 13—13 of Fig. 1. Fig. 14 is a detail vertical section on the line 14—14 of Fig. 1. Fig. 15 is a detail view of the weighted lever and dog forming part of the inking plate operating means.

Referring to the drawings, 1 designates the frame of the press on which is journaled a horizontal transverse drive shaft 2 which may be operated by any suitable power, a foot power mechanism being shown in the present instance consisting of a treadle lever 3 and a connecting rod 4 coupling the same to a crank 5 on the shaft. The shaft 2 carries at one end a fly wheel 6 and at its opposite end a gear pinion 7, which latter meshes with a gear 8 on one end of a horizontal transverse countershaft 9, which is provided at its opposite end with a crank disk 10. The gear 8 is provided with a cam groove

or surface 11 in which operates a roller 12 mounted on a crank arm 13 connected with a rock shaft 14 carrying the platen 15, whereby the platen is given a rocking motion into 5 and out of printing position, the movement of the platen when in printing position being limited by a stop arm or member 16 adapted to engage the shaft 9.

Bolted or otherwise suitably fixed to the 10 frame are rearwardly extending guide bars 17 reinforced from the frame by braces 18, and mounted for sliding back-and-forth movements on these bars are form carriers 19 and 20, respectively provided with guide 15 rails 21 and 22, the front form carrier 19 being provided with sleeves 23 which slidably engage the bars 17 and which are suitably apertured to receive the foot portions 24 of the rear form carrier 20 which slide 20 upon the upper surfaces of said bars. The front form carrier 19 is provided with a suitable opening, preferably formed by the rails 21, to receive the front type form 25 which is locked in the usual manner in a 25 chase 26, the rails and chase being shown as formed with tongue and groove engaging surfaces whereby the chase is adapted to be slidably inserted and removed, it being understood that the inserted chase may rest at 30 its base upon a suitable support or be secured in position in any suitable manner. The rear form carrier 20 is also suitably constructed to receive the rear form 27 locked in a suitable chase 28.

35 The sliding carrier 20, in addition to forming a support for the rear form, also serves as a support for an inking mechanism comprising rocker arms 29 loosely mounted on a transverse shaft 30 to swing in a vertical 40 plane, said arms being provided with guides 31 and 32 for sliding carrier rods 33 and 34 to which are pivoted or otherwise connected in the usual or any suitable manner the bearing brackets or supports for sets of inking rolls 35 and 36, with which are associated the usual anti-friction rollers for travel upon the guide tracks, the rolls 35 being arranged to travel over the tracks 21 to ink the front form, while the rolls 36 50 are arranged to travel over the tracks 22 to ink the rear form. Springs 37 control the movements of the respective carrier rods to permit said rods to have sliding motion and to adapt the rollers to travel over the tracks 55 in the usual way and to bring the surfaces of the rolls in contact with the surfaces of the forms for an efficient inking action. The sets of rolls 35 and 36 are adapted for co-operation with inking plates 38 and 39 of 60 the ordinary or any preferred construction. In the present instance the plate 38 is shown as mounted to rotate upon an axis 40, while the plate 39 consists of a main plate having a recess or countersink at the center in which 65 rotates an auxiliary plate section 39'. The plate 38 is provided with gear teeth 41, meshing with and receiving motion from a gear 42 receiving motion from a shaft 43 carrying a beveled pinion 44 meshing with a gear 45 carried by a shaft 46 on which the 70 plate 39' is mounted, and whereby the plates 41 and 39' are driven from and by the plate 39. The plate 39 is provided with gear teeth 47 engaged by a weighted dog or pawl 48 pivotally mounted upon one end of a weighted lever 49 pivotally supported upon the sliding carrier 20. The weighted arm of this lever is adapted in the sliding movements of the carrier to run in engagement with a contact 50, so that through the force 80 of gravity and the sliding movements of the said carrier 20 the lever and dog will be vibrated to transmit rotary motion to the inking plate 39 in an obvious manner.

The mechanism for sliding the form carriers back and forth and shifting the same into and out of printing position comprises a pair of connecting rods 51 and 52 which are pivotally connected at their forward ends with crank pins 53 and 54 on the disk 90 10 and gear 8, respectively, and which are pivotally connected at their rear ends with the ends of the shaft 30, so that in the rotation of the countershaft 9 from the drive shaft 2 the platen 15 will be rocked into and 95 out of printing position, as previously described, while at the same time the rear printing form will be slidably operated into and out of printing position. For the purpose of operating the front printing form 100 in timed accord with the rear printing form, and at a different rate of speed, an operating and compensating connection between the form carriers is provided, said connection consisting of swinging lever arms 55 which 105 are pivotally connected at their lower ends with the braces 18 at the opposite sides of the press frame and are provided at their upper ends with slots 56 slidably and pivotally receiving pins or studs 57 projecting 110 from the rear form carrier 20, the said lever arms being coupled by links 58 to short arms 59 depending from the sleeves 23 whereby in the forward and backward movements of the sliding carrier 20 corresponding 115 movements will be imparted to the carrier 19. The carriers 19 and 20 when in retracted position are spaced a certain distance apart, for the purpose of permitting of the free and unobstructed operation of the inking rolls 35 and 36, and hence it is necessary to regulate and vary the speeds of forward motion of said carriers in order to bring them into registering and printing position simultaneously. This is accomplished by arranging the links 58 so that in the forward travel of the carriers the carrier 19 will be moved at a sufficiently less rate of speed than the carrier 20 so that at 120 the moment of printing the type forms upon 130

the carriers will be brought exactly into registering position. As stated, the rocker arms 29 swing loosely upon the shaft 30, and for the purpose of communicating rocking motion thereto in the back and forth motions of the carriers connecting rods 60 are provided which are pivotally connected at their forward ends with lugs 61 on the frame 1 and are pivotally connected at their rear ends with crank arms 62 secured to lugs 63 projecting from the rocker arms, so that in the rearward movement of the carriers an upward pull will be exerted on the rocker arms to swing them upwardly and rearwardly, and thereby cause the rollers to move over the printing plates to take up a supply of ink, while on the forward movement of the form carriers the inking rollers will move forwardly and downwardly and ink the forms prior to the time they come into printing position. Gripping fingers 64 are provided to clamp the sheet against the platen and withdraw the printed sheet from contact with the forms. These fingers are operatively connected with the platen and frame in any suitable manner.

In the practical carrying of my invention into effect, part of the matter to be printed in one color is disposed upon the form 25 while the remainder of the matter to be printed in a different color is disposed upon the form 27, and the construction of the type employed is such as to permit the type matter composing the rear form to move through the front form to bring the sets of type matter upon the different forms into alignment for the printing action in which both colors are printed simultaneously. The type 65 upon the rear type form may be of any suitable construction, while the type 66 upon the front type form is provided in its opposite sides with grooves 67 and in conjunction therewith spacers 68 are used, which are preferably three sided; so that in setting up the type composing the matter to be printed by the front form the spacers may have their two parallel sides fitted into the grooves 67 of adjacent type 66 so as to provide spaces or openings 69 for the passage and reception of the type 65 upon the rear form. Thus it will be understood that the type composing the matter upon the rear form which is to be printed in any certain color will be inked by one set of inking rollers with ink of that color, while the type composing the matter upon the front form which is to be printed in another color will be inked by a separate set of inking rollers with ink of the different color, and when the type forms are brought together or closed from the space or open position shown in Fig. 6 to the printing position shown in Fig. 7 the type matter upon the rear form will project through the openings 65 in the front form so that the type faces of

the two forms will exactly register to print the subject matter thereof in the different colors upon the sheet resting on the platen. Of course, it is to be understood that the type matter upon the different forms may be so set up that any portion of a line, paragraph or body of matter may be printed in one color while the remainder may be printed in a different color. By this means the objection to prior presses of this character, which admit only of different lines or paragraphs being printed in separate colors, is avoided in a simple and efficient manner, and provision made so that any letters, cuts, sections or other subdivisions of lines or other portion of matter to be printed may be printed in a color contrasting with the color of the remainder of the matter. While in the present instance two forms only are shown for printing two colors, it will of course be understood that any number of forms may be employed by using, in all except the rear form, type 66 and spacers 68 of the construction shown in Fig. 10 in conjunction with type 65 upon the rear form, the type being of such length as occasion may require so that the faces thereof will register when the forms are brought into closed or printing position.

I claim:

1. In a multicolor printing press, a type form having type passages, a second type form adapted to be extended through said passages to bring the type forms into register for a printing action, and press mechanism for inking and moving the respective press forms at relatively different rates of speed from inking to printing position and vice versa.

2. In a multicolor printing press, a front type form having type passages, a rear type form adapted to be extended through said passages to bring the type forms into register for a printing action, and press mechanism for inking and moving the respective press forms at relatively different rates of speed from inking to printing position and vice versa.

3. In a multicolor printing press, type forms provided with type matter, one of said forms having openings formed by the type matter through which the type matter on the other form is adapted to pass to bring the type surfaces into register for a printing action, means for spreading the type forms for an inking action and bringing them together for a printing action, said means operating to move the respective printing forms at different rates of speed, a platen, an inking mechanism, and suitable press mechanism for operating the aforesaid parts.

4. In a multicolor printing press, a type carrier, a type form supported thereby embodying type and spacers coöperating there-

- with to provide passages in the type form, a second type form provided with type adapted to enter said passages to bring the type forms into register for a printing action, 5 and a press mechanism including inking means and means for moving the respective type forms at different relative rates of speed from inking to printing position and vice versa.
- 10 5. In a multicolor printing press, a type carrier, a type form supported thereby having type provided with grooves and spacers adapted to fit within grooves of adjacent type and to form passages between certain portions of the type matter, a second type carrier, a type form supported thereby and having type adapted to pass through said passages to bring the type forms into register for a printing action, a platen, inking devices, and press mechanism for operating said inking devices and adapted upon the retraction of the platen to spread the forms apart for an inking action and upon the printing movement of the platen to bring the forms into coöperative printing position. 15
6. In a multicolor printing press, the combination of a platen, type forms arranged one in rear of the other, the front type form having openings through which the type matter on the rear type form is adapted to pass to bring the forms into registering position for printing, an inking mechanism including separate sets of inking rolls 30 for inking the respective type forms, and a press mechanism for actuating the platen and sets of inking rolls and including means for moving the forms forward and backward into and out of printing position, said 35 means being adapted to move the rear form at accelerated speed with relation to the front form. 40
7. In a multicolor printing press, the combination of a platen, a plurality of printing forms arranged one in rear of the other and slidable toward and from the platen, the forward printing form or forms having passages for type matter upon the rear printing form or forms, sets of inking rollers for inking the respective printing forms when in separated relation, and a press mechanism for actuating the platen, printing rollers and sliding forms, said mechanism being operated to slide the printing 55 forms at different rates of speed so as to bring them together on the forward motion and separate them on the rearward motion. 60
8. In a multicolor printing press, the combination of a platen, a plurality of forwardly and rearwardly movable form carriers arranged one in rear of the other, type matter upon the respective forms, the type matter upon the front form or forms being arranged to provide passages for the movement to the printing position of coöperat-
- ing type matter upon the rear form or forms, inking mechanism for inking the type matter upon the different forms in different colors, and press mechanism for actuating the platen, type carriers and inking mechanism, said press mechanism including means for moving the rear form or forms forwardly or rearwardly at accelerated speed with relation to the rear form or forms so as to bring the type matter upon the respective forms into registry on the forward motion and to space the same on the rearward motion. 75
9. In a multicolor printing press, the combination of a frame, a platen, a plurality of type carriers arranged one in rear of the other and movable forwardly and rearwardly with relation to each other and to the platen, sets of inking devices, type matter upon the respective carriers adapted to be inked by said sets of inking devices, the type matter upon the forward carrier or carriers being provided with openings for the reception of the type matter upon the rear carrier or carriers to adapt the same to register for a printing action, a press mechanism for operating the platen and inking devices and including means for shifting one of said type carriers into and out of printing position, and means operated by said type carrier for shifting the other type carrier into and out of printing position at a different rate of speed. 80
10. In a multicolor printing press, and in combination with a press mechanism embodying a plurality of forms and inking devices therefor, type matter upon one of the forms comprising grooved type and spacers adapted to engage the grooves of adjacent type to form passages in said type form, 100 said passages being adapted to receive the type matter upon another form so as to permit the type faces of the different forms being brought into registration for a simultaneous printing action. 110
11. In a multicolor printing press, a type carrier carrying a type form including individual type arranged to provide spaces between the individual type in the various lines of the form, a second type carrier having a type form including individual type adapted to extend from the rear through the spaces in the first-named type form, to bring the type faces of the respective forms into printing registry, and press mechanism for inking said forms and moving the type carriers apart for an inking action and bringing them together for a printing action. 115
12. In a multicolor printing press, type forms provided with set-up type matter, the type matter of one of the forms being spaced to provide passages and the type matter of the other form being adapted for movement through said passages, whereby the forms are adapted to be moved into and out of 120 130

printing registry, press mechanism for inking and moving the respective forms from inking to printing position and vice versa, and compensating means forming part of
5 said mechanism for varying the speed of movement of one of the type forms, with respect to that of the other.

In testimony whereof I affix my signature in presence of two witnesses.

MAX KRAVITZ.
